Primary Examiner — Ian F Whitmore*(74) Attorney, Agent, or Firm* — Fish & Richardson P.C.(57) **CLAIM**

The ornamental design for a display panel portion with graphical user interface, substantially as shown and described.

DESCRIPTION

FIG. 1 is a front view of a display panel portion with graphical user interface, showing a first embodiment thereof; and,

FIG. 2 is a front view of a display panel portion with graphical user interface, showing a second embodiment thereof.

The outermost broken-line perimeter illustrates a portion of a display panel and forms no part of the claimed design. The remaining broken lines illustrate portions of a graphical user interface and form no part of the claimed design. The broken lines do not form claim boundaries.
